COMBINATION WEIGHT BOX AND GUIDE
FOR ELEVATOR GATES AND THE LIKE

Nicholas R. Guilbert, Jr., Chestnut Hill, Pa.

Application October 26, 1945, Serial No. 624,796

1 Claim. (Cl. 16—94)

1

Freight elevators are customarily provided with vertically slideable gates constrained to move in a definite path by some form of guiding means and counterbalanced by weights disposed adjacent each side of the gate and respectively connected therewith by a cord running over a suitably positioned sheave, the weights being enclosed in vertically extending boxes which not only protect them but also to some extent guide them as they move in opposition to the gate.

It is therefore an object of my invention to provide a combination weight box and gate guide for elevator gates and the like which is made entirely of metal, is of extremely simple construction, occupies a minimum of room, which may be arranged to permit ready access to the weights for inspection or adjustment and which provides a rigid and efficient guide or track for the guide clips carried by the gate by means of which, through cooperation with the track, it is held at all times in vertical position.

Other objects and novel features of design, construction and arrangement comprehended by the invention are hereinafter more particularly pointed out or will be apparent to those skilled in the art from the following description of the embodiment thereof illustrated in the accompanying drawing in which:

Fig. 1 is a fragmentary perspective view of my combined weight box and gate guide with a column of weights suspended therein, a part of the guide being broken away to facilitate illustration:

Fig. 2 is a fragmentary side view showing brackets associated with the device for securing it in the elevator hatchway; and

Fig. 3 is an enlarged transverse section substantially on line 3—3 in Fig. 2 with a portion of the gate and one of its guide clips indicated in dotted lines in cooperative association with the guide or track afforded by the invention.

Like characters of reference are used to indicate the same parts in the several figures.

More particularly and as shown in the drawing, my combined weight box and gate guide essentially comprises two complementary members each preferably formed of sheet metal and generally designated as 1, 2. Member 1 is of rectangular channel shape comprising two parallel sides 3, 4 and a base 5, the metal being of sufficiently heavy gauge to insure the requisite stiffness. The other member 2, preferably formed of lighter gauge metal since its duty is less than that of member 1, is of right angle section and so comprises sides 6, 7, the former having a narrow inwardly turned flange 8 on its free edge

extending parallel to side 7, while the latter likewise has a narrow outwardly turned flange 9 at its free edge extending normal to the side and thus parallel to side 6. Both of the members desirably are respectively so proportioned that the overall distance between the free edge of flange 9 and the outer face of flange 8 of member 2 measured parallel to side 6 is slightly less than the distance between the inner faces of sides 3, 4 of member 1, while the length of the sides of the latter preferably approximates the distance between the outer face of flange 9 and the inner face of side 6 of member 2 measured parallel to its side 7.

It results that member 2 can be telescoped in member 1 as best shown in Fig. 3 so that its flanges 8, 9 will respectively abut the base 5 and side 3 of member 1. Side 4 of member 1 is then spaced from member 2 by a distance slightly greater than the width of flange 9 but extends parallel to side 7 of the said member and thus forms a guide extending for the length of the device adapted to be received between the arms *a—a* of a gate clip C of ordinary construction secured to the lateral edge of an elevator gate G as indicated in dotted lines in Fig. 3.

The two members 1, 2 may be operatively secured together in any suitable way as by welding flanges 8, 9 of member 2 to the adjacent portions of member 1 after the members are assembled, or flange 9 and the base of member 1 may be drilled at longitudinally spaced intervals for the passage of bolts 10 carrying nuts 11 on their extremities, in which case flange 8 is usually not connected with the adjacent side 3 of member 1 but merely rests against the latter. To facilitate assembly of the members when the separable or bolted construction is employed, bolts 10 are preferably provided with square heads the diagonals of which are a little longer than the width of the space between side 4 of member 1 and side 7 of member 2 so that the heads will jam between these parts and so obviate the necessity of holding them with a wrench while nuts 11 are being set up.

Since in most installations it is desirable to permit access to the column of weights W which are suspended within the casing formed by the juxtaposed members 1, 2, the separable construction just described may be advantageously employed in the lower half of the combined weight box and guide so member 2 may be removed to expose the weights when they are in lowered position, while the non-separable construction in which the members are welded together may be

used in the upper half of the assembly as indicated in Fig. 1.

The device may be supported in operative position adjacent the path of gate G in any convenient way as, for example and as shown, by angle brackets B welded at intervals to the base of member I and bolted to the wall of the hatchway or other convenient part of the building structure S, one device being of course installed on each side of the hatchway with guides 4 in alignment for reception in the guide clips on the respectively adjacent sides of the gate, thus forming tracks which through cooperation with the clips constrain the gate to move in a vertical path as it is raised and lowered.

It will now be apparent the invention provides a combined weight box and gate guide of simple design which may be produced at relatively low cost and is extremely efficient for its intended purpose. It of course can be made of any required length and in its preferred embodiment, in which the members are separable in its lower half, affords convenient access to the weight column when required although, when assembled, fully enclosing the latter at all times, while the track or guide 4 being integral with that portion of channel member I which forms a part of the weight casing proper is stiffened and braced by the latter and so tends to remain in proper alignment which is a matter of distinct importance as owing to its position it is frequently called on to resist the impact of trucks and the like while they are being moved into and out of the elevator by careless workmen.

While I have herein referred more particularly to the use of the invention in connection with elevator gates, it will be appreciated it may

be employed with equal utility in connection with vertically slideable doors or the like whether forming part of an elevator or some other type of structure.

Having thus described my invention, I claim and desire to protect by Letters Patent of the United States:

A combined weight box and guide for elevator gates comprising an elongated member of rectangular channel section, a second member of right angle section having an outturned flange on one longitudinal edge and an inturned flange on the other and lying substantially within the first member with its outturned flange abutting the base and its inturned flange a side of the latter, means permanently securing said flanges to the channel member, a third member substantially similar to the second member lying in the channel member in prolongation of the second member, and means removably securing the outturned flange of the third member to the base of the channel member, the other side of the latter thus lying in spaced relation to the proximate sides of the other members.

NICHOLAS R. GUILBERT, JR.
